UNITED STATES PATENT OFFICE.

ALBERT T. HILAMAN AND JOSEPH H. CLOUGH, OF LUKE, MARYLAND.

AUTOMATIC STOCK-REGULATOR FOR PAPER-MAKING MACHINES.

No. 920,741.

Specification of Letters Patent.

Patented May 4, 1909.

Application filed March 5, 1908. Serial No. 419,360.

To all whom it may concern:

Be it known that we, ALBERT T. HILAMAN and JOSEPH H. CLOUGH, citizens of the United States, residing at Luke, in the county of Allegany and State of Maryland, have invented certain new and useful Improvements in Automatic Stock-Regulators for Paper-Making Machines; and we do declare the following to be a full, clear, and exact description of the invention, such as will enable others skilled in the art to which it appertains to make and use the same.

This invention relates to an automatic stock regulator for paper making machines.

The object of the invention is to produce a simple and efficient apparatus for automatically regulating the stock to be fed to a paper making machine to secure uniformity in the thickness and weight of the paper.

In the accompanying drawings, Figure 1 is a front elevation partly in section of a stock chest equipped with this improved regulator, partly in section. Fig. 2 is a longitudinal section thereof. Fig. 3 is a detail. Fig. 4 is a top plan of one of the weights.

In the embodiment illustrated a main box or stock chest 1 is shown, having a compartment 2 arranged therein in which a balanced hopper or funnel member to be described appears.

In one wall of the compartment 2 is an opening 3, provided with a closure, preferably in the form of a vertically slidable gate 4, carried by one end of a rod or post 5, and mounted in guides, as 6, disposed at opposite sides of the opening 3. A rack bar 7 is adjustably mounted on said rod 5, preferably by means of spaced collars, as 8, which encircle said rod 5, and one of which is provided with a set screw 9, for adjustably securing the rack 7 to the rod 5.

Two standards 10 and 11 are fixed to the top of the chest 1 with an arched bar 10', connecting them, and through which the rod 5 passes, and is guided thereby, and a shaft 12 is journaled to turn said standards.

A toothed segment 13 is mounted between the free ends of an approximately V-shaped member 14, through which the shaft 12 passes and to which the segment is fixed by set screws, as 14', passing through the arms of said member 14 and engaging said shaft. The segment 13 is positioned to mesh with the rack bar 7.

A flexible element 15 is connected at one end with said V-shaped member 14 and

passes over a pulley 16, mounted on a suitable support, and is provided at its other end with a weighted member 17, for a purpose to be described.

A hopper or funnel-shaped member 18 is disposed in said compartment 2, and is preferably provided with a bail handle 19. This member 18 is suspended from the shaft 12 by means of a chain or other suitable element 20, connected at one end to said bail 19, and at its other end to a member 21 fixed to and extending laterally from said shaft 12. This member 21 is preferably made V-shaped with collars as 22, formed on the free ends thereof, and which encircle the shaft 12, and are fastened thereto by means of set screws as 23.

A spout 24 is arranged opposite the gate 4 and opens into the funnel 18, to convey the stock which flows through said gate into the funnel.

The funnel or feeding hopper 18 is provided at its lower reduced end with an opening 25, having an adjustable closure in the form of a gate 26, carried by the lower end of a rod 27, which passes through an arm 28, extending laterally over the side of the funnel near its top. This rod 27 is screw threaded at its upper end and is provided with a nut 29 adapted to be adjusted on said rod to raise or lower the gate 26 to vary the size of the opening 25, to limit the amount of stock which passes therethrough.

An outlet pipe 30 leads from the compartment 2 and conveys the stock therefrom to the machine.

The main box or chest is provided with an inlet 31 for the stock forced into the box from a pump, (not shown), and 32 is an outlet for the overflow or stock not needed in the machine.

In the operation of this automatic regulator the weights on the member 17 are adjusted to balance the funnel member 18 when it is filled to the desired point with the stock to be fed into the machine, with the segment 13 and the rack bar 7 and the gate rod 5 in mesh, thereby holding the gate 4 open a proper distance to permit the required amount of stock to pass therethrough to the funnel, and from which it passes through the gate 26 into the compartment 2, and out through the pipe 30 to the machine. The size of the opening 25 in the funnel is adjustable by hand by operating the nut 29 on the gate rod 27.

Should the funnel be filled beyond the de-

sired point it overbalances the weight 17, causing the segment 13 to move the rack bar downward and thereby lower the gate 4, and cut off the supply of stock therethrough. On the other hand should the stock in the funnel fall below the balancing point the funnel rises and the weight falls, thereby moving the rack bar upward and opening the gate 4, to permit more stock to flow therethrough into the funnel. The stock from a pump (not shown), is admitted through the inlet 31, and when it reaches a predetermined limit it flows out through the overflow 32.

The weight carrying member is preferably constructed as shown in Fig. 2, being composed of a rod 17 having a hook at one end for engagement with the member 15 and a stop 17^e at its other end. Weights as 17^e of ordinary construction and various sizes are adapted to be removably carried by the rod 17 to provide for the counter-balancing of the hopper when filled to different heights. These removable weights are preferably made in the form shown in Fig. 4.

An auxiliary weight 33 is preferably mounted on the shaft 12. This weight 33 is slidably and adjustably mounted on an arm 34 fixed to the shaft 12 preferably by means of a set screw 35 which passes through a sleeve 36 carried by the weight 33.

We claim as our invention:—

1. An automatic stock regulator comprising a stock receiving tank or chest having an opening provided with an adjustable closure, a vertically movable feed hopper arranged to receive the stock flowing from said chest and connected to open or close said closure on the rise and fall of the hopper, said hopper having an adjustable stock outlet, and counter-balancing means connected with said hopper.

2. An automatic stock regulator comprising a stock receiving chest having an opening provided with an adjustable closure, a rod connected with said closure, a rack

thereon, a toothed segment mounted to mesh with said rack, a weight carried by said segment, and a feed hopper arranged to receive stock from said chest and connected to operate said segment to raise and lower said rack bar and the closure connected therewith to regulate the supply of stock fed to the hopper.

3. An automatic stock regulator comprising a stock receiving chest having an opening provided with an adjustable closure, a rod connected with said closure, a rack thereon, a toothed segment mounted to mesh with said rack, a weight carried by said segment, and a feed hopper arranged to receive stock from said chest and connected to operate said segment to raise and lower said rack bar and the closure connected therewith to regulate the supply of stock fed to the hopper, and an adjustable opening in said hopper for permitting the stock to pass therethrough to the machine.

4. An automatic stock regulator comprising a stock receiving chest having an opening provided with an adjustable closure, a rod connected with said closure and having a rack bar adjustable thereon, a horizontally disposed shaft journaled to turn on said chest, a toothed segment fixed to said shaft in position to mesh with said rack, a weight connected with said segment, a member fixed to and extending laterally from said shaft opposite said segment, a feed hopper arranged to receive stock from the delivery opening of said chest and connected with said laterally extending member, and an adjustable delivery opening in said hopper.

In testimony whereof we have hereunto set our hands in presence of two subscribing witnesses.

ALBERT T. HILAMAN,
JOSEPH H. CLOUGH.
